UNITED STATES PATENT OFFICE.

JAMES CLARENCE BURNE, OF WEST CHELMSFORD, MASSACHUSETTS.

TRANSMISSION-BAND MATERIAL.

Application filed September 12, 1921. Serial No. 499,973.

To all whom it may concern:

Be it known that I, JAMES CLARENCE BURNE, a citizen of the United States, residing at West Chelmsford, in the county 5 of Middlesex and State of Massachusetts, have invented new and useful Improvements in Transmission Band Materials, of which the following is a specification.

This invention relates to transmission bands such as are used for gripping and holding the various drums of a planetary transmission such as is used on a Ford automobile, and has for its object the provision of a novel band lining which will not glaze 10 and consequently become useless when run in oil. Ordinarily such band lining is made of woven fabric, asbestos fiber, other fibrous materials having cork inserts, and various other substances. It has, however, been as- 15certained from long experience that band linings of such material shortly become useless. Owing to the fact that the oil in which the drums rotate burns into the cotton bands they become hard and glazed so that they 20lose their gripping action, the cork inserts break up and the pieces interfere with the magneto action. It is with these objections 25in view that the present invention has been designed.

More specifically, the object of the invention is the provision of a band lining which is constructed entirely or partly of animal material, such as camel's hair or the like which, being naturally oily, is in its element 30when saturated with the oil used in the transmission of an automobile.

With the above and other objects and advantages in view, the invention consists in the details of construction to be hereinafter 40more fully described and claimed and illustrated in the accompanying drawings in which,

Figure 1 is a side elevation of a band having a lining constructed in accordance 45with my invention,

Figure 2 is a plan view of the lining alone,

Figure 3 is a cross-sectional view there- 40through in the line 3—3 of Figure 2 and

Figure 4 is a longitudinal section on the 50 line 4—4 of Figure 2.

Referring more particularly to the drawings the letter A designates a contractile band of the ordinary type which is provided on its inner periphery with a suitable lining. In carrying out the present invention I provide a lining which is designated by the numeral 10 and which is woven from a suitable filler thread such as cotton, or the like and animal hair, preferably 55 camel's hair. The transverse strands of the filler thread are indicated by the numeral 11 and the longitudinal strands of camel's hair are indicated by the numeral 12. The camel's hair is woven in and out of the 60 filler threads in a well known or conventional manner and may extend entirely to the edges of the bands or may extend only to the dot and dash lines on Figure 2 of the drawings with a selvage 13 of cotton or 65 other material if preferred.

In the use of a band lining of this material it will be seen that there will be no hardening or glazing for the reason that camel's hair is naturally oily and is there- 70fore in its proper element and in a natural state when saturated with oil.

While I have shown and described the preferred embodiment of my invention it is of course to be understood that I reserve 75 the right to make such changes in the form, construction and arrangement of parts as will not depart from the spirit of the invention or the scope of the subjoined claim.

Having thus described my invention I 80claim:

A transmission band lining consisting of a base formed of transverse strands of fiber 85filler threads and longitudinal strands of animal hair, the side edges of the band hav- 90ing the outermost longitudinal strands formed of fiber thread to define a selvage of base material.

In testimony whereof I affix my signature.

JAMES CLARENCE BURNE.
